PROCESS AND APPARATUS FOR DIGESTING
FIBROUS MATERIALOtto C. Schoenwerk, Chicago, Ill., assignor to
Chemipulp Process, Inc., Watertown, N. Y., a
corporation of New York

Application May 4, 1932. Serial No. 609,299

27 Claims. (Cl. 92—7)

This invention relates to improvements in digesting systems, and more particularly to a novel system of the type in which hot gases, vapors and liquors, vented from digesters during the cooking 5 of fibrous material, are employed to heat cooking liquor in an accumulator, from which hot preconditioned cooking liquor is taken for use in a subsequent cook.

Heretofore, it has been proposed, after a digester is charged with wood chips or the like, to pump hot cooking liquor from an accumulator into the digester while venting air from the digester to the atmosphere. When acid gas commences to escape, the air vent is closed and the 15 acid gas is diverted to a cooking liquor storage tank. Afterwards, as soon as the digester is completely filled by the liquor, the operation of the pump is continued to pump a relatively high pressure on the substances within the digester. Then 20 the digester is sealed and left under pressure for a time sufficient to permit the liquor to penetrate the fibrous material undergoing treatment. Subsequent to this period, steam is turned into the digester, and during the cooking operation, venting 25 of gases and vapors takes place through the top of the digester, and venting of liquor takes place through the side of the digester. These relief fluids, during the cooking operation, are fed into the accumulator for the purpose of absorbing acid gas and preheating and preconditioning the cooking liquor in the accumulator.

The primary purpose of this invention is to improve systems of that type so as to produce the same quality pulp in a shorter cooking time; to economize on the amount of equipment required; to maintain a higher temperature in the accumulator, and to permit better control over the acid strength and temperature in the accumulator.

46 A further object is to furnish a method and means whereby without employing any special complicated regulating devices, one can maintain a pressure in the main relief header that is almost constant at say 18 pounds, which means 45 that the blow down period during which the gases have to vent through the side relief header is materially reduced.

Another object is to simplify the equipment and to eliminate certain relief headers not necessary in working in accordance with my invention.

50 With the foregoing objects outlined and with other objects in view which will appear as the description proceeds, the invention consists in the novel features hereinafter described in detail, 55 illustrated in the accompanying drawing, and

more particularly pointed out in the appended claims.

The drawing shows an end elevation of my improved apparatus used in practicing the process.

Referring to the drawing, 1 designates a digester, and 2 an accumulator. It will be understood that I contemplate using either one or more digesters in combination with the single accumulator 2.

3, 4, 5 and 6 designate respectively, headers 60 which run parallel to the digesters, the header 3 being the cold gas vent, the header 4 the hot gas and vapor vent, 5 the side liquor vent, and 6 the header for feeding the preconditioned and pre-heated cooking liquor from the accumulator, to 70 the digester.

A gas or vapor vent branch 7, having a control valve 8 leads from the top of each digester to a cross 9, and the upper branch of the cross is connected by a pipe 10 having a valve 11, to 75 the cold gas header 3. A conduit 12 having a valve 13, connects one arm of each cross to the hot gas and vapor header 4. A side relief branch 14 having a valve 15 connects each digester to the header 5, and at the point where the branch 80 14 connects with the header 5, an upstanding pipe 16 having a valve 17, connects the header 5 to the downwardly extending arm of the cross 9. A single conduit 18 arranged at the same elevation as the vent pipes 7 of the digesters, 85 connects the header 4 with the gas or vapor inlet of an upper eductor 19. The outlet of this eductor is directed downwardly and is connected to a down pipe 20 which leads to the inlet of a lower eductor 21 that is connected by a pipe 90 22 to the accumulator.

The side relief header 5 is also connected to the inlet of the last mentioned eductor by the following means. A down pipe 23 having a check valve 24 is connected to a T 25, the upper branch 95 of which is connected to a pipe 26 having a control valve 27. Pipe 26 leads to the suction of a continuously operated pump 28, the discharge of which is connected by a pipe 29 to the inlet of the lower eductor 21.

In order that liquor may be circulated through the accumulator and the eductor 21 by means of the pump 28, a pipe 30 having a valve 31, leads to a second T 32 that is connected with the T 25.

Hot preconditioned liquor from pipe 30 can 105 be fed to the header 6 by means of a pump 33, the suction of which is connected by a pipe 34 to the T 32, and the discharge of which is connected by a pipe 35 to the header 6.

Hot liquor from the last mentioned header may 110

be introduced into any one of the digesters by branch pipes 36 that join the header to the digesters. Each of these branches has a control valve 37 and a check valve 38.

5 Liquor from an acid storage tank 39 is forced from the same by a pump 40, the suction of which is joined to the storage tank by a pipe 41 having a control valve 42. An upstanding pipe 43 joins the discharge of the pump to a 10 check valve 44 leading into the inlet end of the upper eductor 19.

The cold air or gas header 3, has a valve 45 which permits this header to discharge to atmosphere during the filling of a digester, but as 15 soon as acid gas appears in the header, it can be diverted by a pipe 46 which leads from the header 3 into the storage tank 39.

Any excess gas accumulating in the accumulator can be led to the storage tank by means of 20 a pipe 47 having a control valve 48.

Each digester has a gauge glass 49, and the accumulator also has a gauge glass 50.

It will be noted that by using two eductors, that is, the one 19 at the top, and the one 21 25 at the bottom of the drop leg 20, and by bringing the side relief liquor into the suction side of the lower eductor pump 28, only one main relief header is required, that is, the header 4. The header 3 is installed in accordance with 30 prior practice, with the valve 45 opening into the digester room. The second header 5 is provided to take care of the side relief separately from the top or gas relief.

As an illustration of the use of my new method, the digester is filled in the usual way, and then the cover is bolted on, and the valve 31 at the bottom of the accumulator is opened. The pump 33 is then started, and liquor is pumped into the digester until the same is completely filled with chips or the like and liquor. 35 During this time, of course, valves 8, 11 and 45 are opened, and valves 13, 17 and 15 are closed. As soon as acid gas appears at the valve 45, that valve is closed, and the gas which arises from 40 the liquor during the filling is then vented through the pipe 46 into the acid storage tank. As soon as the digester is completely filled by the liquor which is always evident by the change in sound of the liquor flowing through valve 45 45 50 55 60 65 70 75 80 85 90 95 100 105 110 115 120 low pressure gases and vapors were sent to the storage tanks where a proportion of the heat is dissipated, due to the fact that such tank is normally located outdoors. In my improved method, these gases and vapors are conducted to the accumulator, and therefore, the temperature of the liquor in the latter may be maintained at a higher degree, and furthermore, this enables one to have better control over the acid strength and 10 temperature in the accumulator.

Also, in accordance with my invention, without employing any special complicated regulating devices, I can maintain a very low pressure in the relief header 4, which means again that the 15 blow down period during which the gases have to vent through the header 5 is materially reduced.

Furthermore it will be noted that in an apparatus according to the invention, the gas and 20 vapor inlet pipe 18 of the upper eductor 19 can be located on the same level as the branches 7 of the digestors, and this makes the apparatus function more smoothly. The arrangement is such that one can maintain a very low pressure 25 in the line 4 even with a great number of digesters in a plant. The arrangement has worked successfully in a plant where six digesters were used in connection with a single accumulator.

In actual practice, the pump 28 would normally be located on approximately the same level 30 as the pump 33 in order to keep the suction lift as low as possible.

From the foregoing it is believed that the construction of the apparatus and steps of the method may be clearly understood by those skilled in the art, and I am aware that changes may be made in the details of the apparatus and in the sequence of steps of the method, without departing 40 from the spirit of the invention, as expressed in the claims.

What is claimed and desired to be secured by Letters Patent is:

1. In the chemical cooking of fibrous material, venting a relief fluid from a digester during the 45 cooking period, circulating an acid liquor by pumping the same in an annular path, and introducing said relief fluid into the circulating liquor at the suction side of the pump.

2. In the chemical cooking of fibrous material, venting gases and vapors from a digester during the cooking period, circulating acid liquor in an annular path by a pumping operation, and introducing said relief gases and vapors into the 55 circulating stream of acid liquor at the suction side of the pump.

3. In the chemical cooking of fibrous material, venting side relief liquor from a digester during the cooking period, circulating acid liquor in an annular path by a pumping operation, and introducing said side relief liquor into the circulating stream of acid liquor at the suction side 60 of the pump.

4. In the chemical cooking of fibrous material, pumping a stream of acid liquor, and utilizing the force of the moving stream for lowering the pressure in the digester during the blow down period of the cooking operation.

5. In the chemical cooking of fibrous material, pumping a stream of acid liquor, and utilizing the force of the moving stream for lowering the pressure in the digester during the blow down period of the cooking operation by withdrawing 75 gases and vapors from the top of the digester during the blow down period and introducing the

same into the stream at the suction side of the pump.

6. In the chemical cooking of fibrous material, pumping an endless stream of acid liquor through an accumulator, and utilizing the suction exerted by the pump for withdrawing gases and vapors from a digester during the blow down period of the cooking operation, and for introducing said gases and vapors into said stream, whereby the lowering of the pressure in the digester is accelerated during the blow down period. 80 85

7. In a process of the character described, forcing acid liquor from a storage tank through first and second eductors arranged in series, into an accumulator, simultaneously circulating a stream of acid liquor by pumping the same through the second eductor and accumulator, utilizing the suction of the first eductor for withdrawing relief fluid from a digester, and utilizing the suction of the pump also for withdrawing relief fluid from the digester. 90 95

8. In a process of the character described, forcing acid liquor from a storage tank through first and second eductors arranged in series, into an accumulator, simultaneously circulating a stream of acid liquor by pumping the same through the second eductor and accumulator, utilizing the suction of the first eductor for withdrawing relief fluid from a digester utilizing the suction of the pump also for withdrawing relief fluid from the digester, and mixing the first mentioned relief fluid with acid liquor in the first eductor. 100 105

9. In a process of the character described, forcing acid liquor from a storage tank through first and second eductors arranged in series, into an accumulator, simultaneously circulating a stream of acid liquor by pumping the same through the second eductor and accumulator, utilizing the suction of the first eductor for withdrawing relief fluid from a digester, utilizing the suction of the pump also for withdrawing relief fluid from the digester, and mixing the second mentioned relief fluid with the circulating liquor. 110 115

10. In a process of the character described, forcing acid liquor from a storage tank through first and second eductors arranged in series, into an accumulator, simultaneously circulating a stream of acid liquor by pumping the same through the second eductor and accumulator, utilizing the suction of the first eductor for withdrawing relief fluid from a digester, utilizing the suction of the pump also for withdrawing relief fluid from the digester, and simultaneously mixing the first mentioned relief fluid with acid liquor in the first eductor, and the second mentioned relief fluid with the circulating liquor at the suction side of the pump. 120 125 130

11. In a process of the character described, discharging relief fluid from the top of a digester through a horizontally disposed passageway, introducing said fluid in the same horizontal plane into the gas inlet of an eductor, and simultaneously forcing acid liquor through said eductor for maintaining a substantially constant pressure in said passageway. 135 140 145

12. In a process of the character described, simultaneously discharging relief gases and vapors from the tops of a number of digesters into a horizontally disposed passageway having branches arranged in the same horizontal plane as the passageway, discharging said gases and vapors from the passageway into the gas inlet of an eductor, said inlet also being arranged in the same horizontal plane as the passageway, and 150

simultaneously forcing acid liquor through the eductor for maintaining a substantially constant pressure in said passageway and its branches.

13. An apparatus for the chemical cooking of fibrous material, comprising a pressure accumulator, a pipe leading from the accumulator back to the accumulator, a pump interposed in said pipe, a digester, and a relief conduit for the digester leading from the latter to the pipe anterior to said pump.

14. An apparatus for the chemical cooking of fibrous material, comprising an accumulator, a pipe leading from the accumulator back to the accumulator, a pump interposed in said pipe, a digester, a relief conduit for the digester leading from the latter to the pipe anterior to said pump, and a side relief header interposed in said conduit.

15. An apparatus for the chemical cooking of fibrous material, comprising a pressure accumulator, a pipe leading from the accumulator back to the accumulator, a pump interposed in said pipe, a digester, a relief conduit for the digester leading from the latter to the pipe anterior to said pump, a side relief header interposed in said conduit, and a valve in the conduit between the digester and said header.

16. An apparatus for the chemical cooking of fibrous material, comprising an accumulator, a pipe leading from the accumulator back to the accumulator, a pump interposed in said pipe, a digester, a relief conduit for the digester leading from the latter to the pipe anterior to said pump, a side relief header interposed in said conduit, and a check valve in the conduit between said header and said pipe.

17. An apparatus for the chemical cooking of fibrous material, comprising a pressure accumulator, a pipe leading from the accumulator back to the accumulator, a pump interposed in said pipe, a digester, a relief conduit for the digester leading from the latter to the pipe anterior to said pump, and an eductor in said pipe posterior to said pump.

18. An apparatus of the character described, comprising a digester, an accumulator, a storage tank, a first eductor, a first pipe connecting the storage tank to the first eductor, a pump interposed in said pipe for forcing liquor from the storage tank to said eductor, a second pipe connecting the outlet of the eductor to the accumulator, a second eductor interposed in the second pipe, a third pipe connecting the accumulator to the inlet of the second eductor, a second pump interposed in the third pipe, a first valved conduit connecting the top of the digester to the first eductor, and a second valved conduit connecting the first conduit to said third pipe anterior to the second pump.

19. An apparatus of the character described, comprising a digester, an accumulator, a storage tank, a first eductor, a first pipe connecting the storage tank to the first eductor, a pump interposed in said pipe for forcing liquor from the storage tank to said eductor, a second pipe connecting the outlet of the eductor to the accumulator, a second eductor interposed in the second pipe, a third pipe connecting the accumulator to the inlet of the second eductor, a second pump interposed in the third pipe, a first valved conduit connecting the top of the digester to the first eductor, a second valved conduit connecting the first conduit to said third pipe anterior to the second pump, and a gas and vapor header interposed in the first conduit.

20. An apparatus of the character described, comprising a digester, an accumulator, a storage tank, a first eductor, a first pipe connecting the storage tank to the first eductor, a pump interposed in said pipe for forcing liquor from the storage tank to said eductor, a second pipe connecting the outlet of the eductor to the accumulator, a second eductor interposed in the second pipe, a third pipe connecting the accumulator to the inlet of the second eductor, a second pump interposed in the third pipe, a first valved conduit connecting the top of the digester to the first eductor, a second valved conduit connecting the first conduit to said third pipe anterior to the second pump, and a side relief header interposed in the second conduit.

21. An apparatus of the character described, comprising a digester, an accumulator, a storage tank, a first eductor, a first pipe connecting the storage tank to the first eductor, a pump interposed in said pipe for forcing liquor from the storage tank to said eductor, a second pipe connecting the outlet of the eductor to the accumulator, a second eductor interposed in the second pipe, a third pipe connecting the accumulator to the inlet of the second eductor, a second pump interposed in the third pipe, a first valved conduit connecting the top of the digester to the first eductor, a second valved conduit connecting the first conduit to said third pipe anterior to the second pump, a side relief header interposed in the second conduit, and a valved side relief branch connecting said digester to said header.

22. An apparatus of the character described, comprising a digester, an accumulator, a storage tank, a first eductor, a first pipe connecting the storage tank to the first eductor, a pump interposed in said pipe for forcing liquor from the storage tank to said eductor, a second pipe connecting the outlet of the eductor to the accumulator, a second eductor interposed in the second pipe, a third pipe connecting the accumulator to the inlet of the second eductor, a second pump interposed in the third pipe, a first valved conduit connecting the top of the digester to the first eductor, and a second valved conduit connecting the first conduit to said third pipe anterior to the second pump, said first conduit having two valves and a gas and vapor header interposed between the digester and the first eductor.

23. An apparatus of the character described, comprising a digester, an accumulator, a storage tank, a first eductor, a first pipe connecting the storage tank to the first eductor, a pump interposed in said pipe for forcing liquor from the storage tank to said eductor, a second pipe connecting the outlet of the eductor to the accumulator, a second eductor interposed in the second pipe, a third pipe connecting the accumulator to the inlet of the second eductor, a second pump interposed in the third pipe, a first valved conduit connecting the top of the digester to the first eductor, a second valved conduit connecting the first conduit to said third pipe anterior to the second pump, a side relief header interposed in the second conduit, and a valve in the second conduit between the first conduit and said header.

24. An apparatus of the character described, comprising a digester, an accumulator, a storage tank, a first eductor, a first pipe connecting the storage tank to the first eductor, a pump interposed in said pipe for forcing liquor from the storage tank to said eductor, a second pipe connecting the outlet of the eductor to the ac-

- 5 cumulator, a second eductor interposed in the second pipe, a third pipe connecting the accumulator to the inlet of the second eductor, a second pump interposed in the third pipe, a first 80
 10 valved conduit connecting the top of the digester to the first eductor, a second valved conduit connecting the first conduit to said third pipe anterior to the second pump, a forth pipe connecting the third pipe to the bottom of the digester, and a pump interposed in the fourth pipe 85
 15 for forcing acid liquor from the accumulator into the digester.
- 20 25. An apparatus of the character described, comprising a digester, an accumulator, a storage tank, a first eductor, a first pipe connecting the storage tank to the first eductor, a pump interposed in said pipe for forcing liquor from the storage tank to said eductor, a second pipe connecting the outlet of the eductor to the accumulator, a second eductor interposed in the second 90
 25 pipe, a third pipe connecting the accumulator to the inlet of the second eductor, a second pump interposed in the third pipe, a first valved conduit connecting the top of the digester to the first eductor, a second valved conduit connecting the first conduit to said third pipe anterior to the second pump, a third valved conduit connecting the first conduit to said third pipe anterior to the second pump, a third valved conduit connecting the first conduit to the storage tank, and an air vent valve interposed in the third conduit. 95
- 30 35. An apparatus of the character described, comprising a digester, an accumulator, a storage tank, a first eductor, a first pipe connecting the storage tank to the first eductor, a pump in- 100
